UNITED STATES PATENT OFFICE.

ISAAC NATHAN, OF OAKLAND, CALIFORNIA.

COMBINED REINFORCE AND SPOT FOR BILLIARD AND POOL TABLES.

1,143,222.

Specification of Letters Patent. Patented June 15, 1915.

Application filed November 7, 1914. Serial No. 870,794.

To all whom it may concern:

Be it known that I, ISAAC NATHAN, a citizen of the United States, residing at Oakland, in the county of Alameda and State of California, have invented new and useful Improvements in Combined Reinforce and Spot for Billiard and Pool Tables, of which the following is a specification.

This invention relates to a novel protector 10 and spot for billiard and pool tables.

On billiard and pool tables the expensive 15 felt surface is rapidly worn in a small area at the middle toward one end by the great frequency with which one of the balls is placed or set up or "spotted" as it is termed.

I have invented and successfully used, a 20 simple device which not only aids in spotting the ball upon the table, but is particularly effective for protecting the immediately surrounding area of the felt against wear.

The invention consists of a polychrome 25 disk of tenacious or durable material, such as a thin fabric provided with an adhesive whereby it may be easily secured to the 30 felt; the device having a central spot of different colors from the rest of the disk for indicating the position at which to place the ball.

The invention consists of the parts and 35 the combination and construction of parts as hereinafter more fully described and claimed, having reference to the accompanying drawings, in which—

Figure 1 is a full scale plan view of the 40 protector. Fig. 2 is a plan of a table with the device applied.

2 indicates a table with a felt surface. The protector comprises a disk 3 of about 45 1½ inches diameter and preferably made of some thin, tough material, as for instance linen or silk fabric, thus affording a substantial wearing body and a smooth surface over which the balls may roll with the least deflection. The disk 3 has an adhesive side for application to the felt table surface.

With this disk such a considerable area is afforded upon which to "spot" the ball that there is but little reason for the surrounding surface to be injured. For the purpose of 50 more precisely indicating the median line of the table the disk has a central area colored differently from the remainder.

The polychrome surface may be produced in any suitable manner and as here shown 55 is accomplished by applying a thin disk 4 of a suitable color to the protector 3, which may be of any other color, here shown as green on black. Preferably the central spot of color is printed or stamped directly 60 on the disk. This not only serves its indicating functions, but particularly is preferred because it cannot peel off as when an extra piece is pasted on.

An important advantage of my protector 65 is that being of larger area than the target spot it covers a larger area of felt and wears a long time. Preventing wear of the felt also protects the slate bed of the table.

Having thus described my invention, what 70 I claim and desire to secure by Letters Patent is—

1. The combination with the felt surface of a pool or billiard table, of a protector 75 for covering the usual "spotting" position of the felt, said protector having a polychrome upper surface, one of the colors of which forms a center for closely indicating the median line of the table.

2. A protector for the felt surface of a 80 billiard or pool table, consisting of a disk with an adhesive side, and a "spot" indicator on the opposite side of different color from the remainder of the disk.

In testimony whereof I have hereunto set 85 my hand in the presence of two subscribing witnesses.

ISAAC NATHAN.
